WILLIAM R. PHILLIPS, OF PORTLAND, OREGON.

METHOD OF FORMING CONCRETE PILES IN PLACE.

1,104,703.

Specification of Letters Patent.

Patented July 21, 1914.

Original application filed March 17, 1911, Serial No. 615,165. Divided and this application filed April 7, 1912. Serial No. 759,561.

To all whom it may concern:

Be it known that I, WILLIAM R. PHILLIPS, a citizen of the United States, and a resident of the city of Portland, county of Multnomah, State of Oregon, have invented a new and useful Improvement in Methods of Forming Concrete Piles in Place, of which the following is a specification.

My invention relates to the construction 10 of concrete piles in place, and has for its purpose to render such construction convenient, expeditious and inexpensive.

To this end my method consists in placing where the pile is to be formed a tubular 15 form set up on end, such form comprising outer and inner shells spaced apart, filling the space between the shells with pile forming material, thereby weighting the form, providing a scouring space at the bottom of 20 the form, scouring away the soil from under the form by a hydraulic stream introduced through the core of the form and providing an outlet through the same core extending upward to the outer and inner shells of the 25 form as the latter is sunk into the ground, and filling such extensions with pile forming material; and finally filling also the scouring space and the core of the form with pile forming material.

30 This is a division of my application filed March 7, 1911, Serial No. 615,165, and now Patent No. 1,063,943, of June 3, 1913.

In the accompanying drawings: Figures 1 to 4, inclusive, represent diagrammatically 35 the method in which my pile construction is carried out; Fig. 1 representing the first or lowermost course of the pile as placed over the spot where it is to be sunk; Fig. 2 representing the pile as having been sunken into 40 the ground to nearly the top of the first course; Fig. 3 illustrating the mode in which the soil is washed from under the pile so as to form a cavity for the pile to sink into; and Fig. 4 showing the completed pile in 45 place; Fig. 5 is an enlarged sectional elevation of the lowest or bottom two courses of the pile, it also illustrates a convenient mode for fastening the courses of the shell of my pile end to end; this view also shows the 50 inner shell of the casing through which the material washed from under the pile is expelled; and Fig. 6 is an enlarged sectional detail of the construction of the same parts shown in Fig. 5, and also shows the lower 55 end of a nozzle-ended pipe, inserted in the

inner shell, for washing away the soil from under the bottom of the pile, so as to obtain a cavity for the latter to sink into.

The pile consists of a sheet metal tubular 60 casing or form, 6, of a cross section suited to the load which the pile has to sustain, or to other conditions regulated by the purpose for which the pile is to be used. The shell is preferably of cylindrical form, and is made up of a plurality of courses joined end 65 to end, so that the pile will be of such ultimate length as required. Centrally within the outer shell, 6, is provided an inner shell 7 spaced from the outer shell. In the bottom 70 of the lower end of the form-section, to be set on the ground, is fastened a recessed or concaved bottom 7 conveniently formed 75 conical like an inverted funnel, and preferably formed with a rim flange 7a, which is riveted in place by rivets 13, in the bottom 80 of the lowest course or section 6a of the outer shell 6.

As more clearly shown in Fig. 6, the bottom edge 5 of the outer section 6a, as well as the edge 7b of the conical part or bottom 7 85 of the inner shell 4, are beveled so as to adapt them to cut into the ground. The widest portion of the bottom 7 is made of such diameter as to just fit snugly the interior of the outer section 6a, and said bottom 7 serves 90 to support the filling 11 off the ground, thereby providing a scouring space at the bottom and within the bottom of the form. The inner shell 4 is built up in length in correspondence with the outer form 6, so as to 95 extend to the top of the uppermost course of the latter. Said inner shell 4 is conveniently constructed of piping of suitable diameter, the pieces thereof being threaded at their opposed abutting ends 4a, and connected by a coupling as 10, the lowermost piece of the inner shell 4 being formed of a half-nipple 9, as shown in Fig. 6. The inner shell 4 constitutes a channel or core through 100 which the soil washed away from under the pile is expelled, as shown by the arrow, b, in Fig. 3. The inner shell 4 is made of such diameter as to permit a jet or hydraulic pipe, 1, to be inserted therein, as shown in Figs. 3 and 6; said pipe being connected at 3 with 105 a suitable head of water, and formed at its bottom end with a nozzle 2; the latter extending preferably at a right angle from the pipe 1.

The manner in which I construct a pile is 110

as follows: The lower section or course of the outer form 6 is set upright over the spot where the pile is to be sunk. The space 11 between the outer and inner shells is then 5 filled with concrete as shown in Fig. 1; a guide frame (not shown) having been previously set up around the form, so as to guide the pile straight when sinking into the ground. The pipe, 1, is then inserted 10 and water under a suitable head is discharged through said pipe, and the latter being manipulated in such manner as to wash away the earth from under the bottom of the form 6. The right angular portion 3 15 of the jet pipe, 1, also serves as a handle, facilitating the manipulation of the latter. The soil washed away from under the form 6 is discharged, together with the water, through the spout 4^a of the inner shell 4, as 20 indicated by the arrows in the lower part and at b in Fig. 3; the arrow, a, in the same figure, represents the inflow of water through said jet pipe 1. As the soil is washed from under the form the weight of 25 the concrete filling 11 will cause the latter to sink in the cavity formed in the soil. When the form has been so far sunk into the ground that its upper end is almost flush therewith the form is extended upward by 30 adding further sections to the outer and inner shells. This may be conveniently done as shown in Figs. 5 and 6, the ends of the outer shell being connected by means of butt straps 8 riveted in place by rivets 14. Next 35 an upper section of the inner shell 4 is fastened in place. The extension of the form so built is then also filled with concrete, and the hydraulic process of sinking the pile is continued. In Fig. 4 the pile is shown as 40 sunk its full depth, and as having the inner shell 4 also filled with concrete, 12, which is the final step in the construction of my pile. In some cases the filling of the outer form 6, as well as the inner shell 4, instead of being of concrete may be sand, or other material which will pack sufficiently to impart solidity to the pile as a whole, and render it adapted to support its load.

One of the important features of my improved method is that all the concrete used in the making of the pile may be inspected, which insures uniformity of the mass.

I claim:

1. The method of forming a concrete pile 50 in place which consists in placing, where the pile is to be formed, a tubular form com-

prising outer and inner shells spaced apart, filling the space between the shells with pile forming material, thereby weighting the form, supporting the filling above the ground so as to provide a scouring space within the bottom of the form, sinking the form by scouring away the soil from under it by a hydraulic stream introduced through the bore of the form, discharging said soil 65 through the bore, extending upward the outer and inner shells of the form as the latter is sunk into the ground, and filling such extensions with pile forming material as required. 70

2. The method of forming a concrete pile in place which consists in placing, where the pile is to be formed, a tubular form comprising outer and inner shells spaced apart, filling the space between the shells 75 with pile forming material, thereby weighting the form, supporting the filling above the ground so as to provide a scouring space within the bottom of the form, sinking the form by scouring away the soil from under 80 it by a hydraulic stream introduced through the bore of the form, discharging said soil through the bore, extending upward the outer and inner shells of the form as the latter is sunk into the ground, filling such extensions with pile forming material as required, and finally filling also the scouring space within the bottom of the form with pile forming material. 85

3. The method of forming a concrete pile 90 in place which consists in placing, where the pile is to be formed, a tubular form comprising outer and inner shells spaced apart, filling the space between the shells with pile forming material, thereby weighting the 95 form, supporting the filling above the ground so as to provide a scouring space within the bottom of the form, sinking the form by scouring away the soil from under it by a hydraulic stream introduced through 100 the bore of the form, discharging said soil through the bore, extending upward the outer and inner shells of the form as the latter is sunk into the ground, filling such extensions with pile forming material as required, and finally filling also the scouring space within the bottom of the form and the bore of the form with pile forming material. 105
